UNITED STATES PATENT OFFICE.

FRANK BORGE AND JOSEPH E. CLARY, OF NEWMAN, CALIFORNIA.

MOLDBOARD ATTACHMENT FOR PLOWS.

SPECIFICATION forming part of Letters Patent No. 611,349, dated September 27, 1898.

Application filed February 2, 1898. Serial No. 668,826. (No model.)

To all whom it may concern:

Be it known that we, FRANK BORGE and JOSEPH E. CLARY, citizens of the United States, residing at Newman, county of Stanislaus, State of California, have invented an Improvement in Moldboard Attachments for Plows; and we hereby declare the following to be a full, clear, and exact description of the same.

10 Our invention relates to a novel means for attaching moldboards to plow-standards and means for readily reversing them.

It consists, essentially, in forming or fixing upon the back of the moldboard a slotted lug or projection, which is adapted to pass through the lug of the standard and to be locked thereto by a key passing through the slot, the projection being so placed with reference to the top and bottom of the moldboard and the latter so shaped that it can be reversed by simply removing it and reversing it, then securing it again in place.

The invention also comprises details of construction, which will be more fully explained 25 by reference to the accompanying drawings, in which—

Figure 1 is a view of the attachment. Fig. 2 shows the moldboard separated.

The object of our invention is to provide a 30 means for readily attaching, removing, and reversing the moldboards of plows, and it is especially adapted to that class of gang-plows locally known as the "Stockton" gang-plow. In this class of plows A is a standard, which 35 is attached to the plow-beam and which has a lug B projecting to one side for the purpose of attaching the moldboard thereto.

The moldboard C is made of the proper curvature and may be of wrought or cast 40 steel, and is in the form of a rhombus with acute and obtuse angles, as shown.

Upon the back of the moldboard is cast, welded, or otherwise attached a projection D, having a slot E made through it.

45 The lug B of the standard has an opening made through it corresponding in shape and size with the projection upon the back of the moldboard, so that the latter may be inserted

in this opening, projecting through it sufficiently so that the slot E is exposed behind 50 the lug.

F is a key which is inserted and driven into the slot, thus drawing the moldboard firmly against the front of the standard-lug and locking it firmly in place. When thus locked, one 55 of the acute angles is presented to the ground essentially in the line of travel of the front edge of the standard, the edge of the moldboard meeting the landside, so as to make a clean cut when the plow passes through the 60 ground. The other acute angle is at the top and at the opposite side of the plowshare, as shown.

The shape of the two ends of the share is such that by removing it from the standard it 65 can be reversed and the bottom becomes the top, the top taking the place of the bottom, so that whenever the share has become dull it may be reversed by simply knocking out the key, reversing the moldboard, replacing, 70 and again locking it in place, the time occupied being very short.

Having thus described our invention, what we claim as new, and desire to secure by Letters Patent, is—

1. The combination of a plow-standard having a lug projecting substantially at right angles from one side thereof, a reversible moldboard fitting said lug and means for locking the moldboard to the lug. 75

2. A plow-standard having a lug and support projecting substantially at right angles from one side thereof, and having an opening formed in it, in combination with a moldboard fitting said lug and having a slotted projection on its back adapted to be passed through the opening in the lug, and a means engaging the slotted projection and locking the moldboard to the lug. 85

3. A plow-standard having a lug or support 90 projecting from one side with an opening made through it, a moldboard having a projection centrally upon the back with a slot therethrough, said projection fitting the opening in the standard-lug, and a key fitting the 95 slot and locking the moldboard to the support.

4. The combination of a plow-standard having a lug projecting substantially at right angles from one side thereof, and provided with an opening, a moldboard fitted to said lug and
5 having a slotted projection centrally placed upon its back and adapted to pass through the opening in the lug, and a key passed through the slot in the projection and adapted to detachably lock the moldboard to the lug,
10 said moldboard having a rhomboidal form

and adapted to be reversed so that either edge may be uppermost.

In witness whereof we have hereunto set our hands.

FRANK BORGE.
JOSEPH E. CLARY.
